CLAIM

The ornamental design for a pocket-size organizer with stand, as shown and described.

DESCRIPTION

FIG. 1 is a perspective view of the pocket-size organizer with stand;

FIG. 2 is a left side view thereof;

FIG. 3 is a front perspective view thereof;

FIG. 4 is a front view thereof;

FIG. 5 is a back perspective view thereof;

FIG. 6 is a right side view thereof; and,

FIG. 7 is a bottom plan view thereof.

The cord is shown broken away in the views in order to indicate an indeterminate length.
